(57) CLAIM

The ornamental design for a garment, as shown and described.

DESCRIPTION

FIG. 1 is a front view of a garment according to the design; FIG. 2 is a rear view thereof;

FIG. 3 is a right side view thereof;

FIG. 4 is a left side view thereof;

FIG. 5 is a front perspective view thereof;

FIG. 6 is a rear perspective view thereof;

FIG. 7 is a front view thereof shown in an environment of use; and,

FIG. 8 is a right side view thereof shown in an environment of use, the left side view being a mirror image thereof.

The portions of the garment shown in dash-dot broken lines in FIGS. 1-8 do not form part of the claimed design. The dash-dot broken line showing of the feet, arms, and torso in FIGS. 7 and 8 is for the purpose of illustrating portions of the environmental structure and forms no part of the claimed design. The dot-dot broken lines shown on the legs of the garment in FIGS. 1-8 are for illustrating the boundary of the design only and do not form part of the claimed design.
